US0D1112579S

(12) **United States Design Patent** (10) **Patent No.:** **US D1,112,579 S**
(45) **Date of Patent:** **** Feb. 10, 2026**

(54) **COMBINED GUN CLEARING AND TEST TRAP**

(71) Applicant: **Timothy Scott Schmalbeck**, Rigby, ID (US)

(72) Inventor: **Timothy Scott Schmalbeck**, Rigby, ID (US)

(73) Assignee: **Timothy Scott Schmalbeck**, Rigby, ID (US)

(**) Term: **15 Years**

(21) Appl. No.: **29/950,805**

(22) Filed: **Jul. 4, 2024**

Related U.S. Application Data

(63) Continuation-in-part of application No. 17/453,695, filed on Nov. 5, 2021.

(57) **CLAIM**

The ornamental design for a combined gun clearing and test trap, as shown and described.

DESCRIPTION

FIG. 1 is an isometric view of a combined gun clearing and test trap, showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the combined gun clearing and test trap, that form no part of the claimed design.

1 Claim, 5 Drawing Sheets
